Atty.

UNITED STATES PATENT OFFICE.

JOHN H. LAWRENCE, OF STERLING, ILLINOIS, ASSIGNOR OF ONE-HALF TO
EDWIN F. LAWRENCE, OF STERLING, ILLINOIS.

RAIL AND BRACKET CONNECTION.

SPECIFICATION forming part of Letters Patent No. 699,195, dated May 6, 1902.

Application filed February 14, 1902. Serial No. 94,091. (No model.)

To all whom it may concern:

Be it known that I, JOHN H. LAWRENCE, a citizen of the United States of America, and a resident of Sterling, in the county of White-
5 side and State of Illinois, have invented cer-
tain new and useful Improvements in Rail
and Bracket Connections, of which the fol-
lowing is a specification.

The present invention relates to means for
10 securing track-rails and the like to the sup-
porting brackets therefor; and the object of
the present improvement is to provide a sim-
ple and efficient construction of the parts
whereby a strong and durable connection of
15 the parts is attained in a ready and econom-
ical manner and with which a rail of a mini-
mum height is left free at top and bottom for
unobstructed track uses, all as will herein-
after more fully appear, and be more particu-
20 larly pointed out in the claims.

In the accompanying drawings, illustrative of
the present invention, Figure 1 is a view
illustrative of the present invention, in which
the bracket member is shown in end eleva-
25 tion and the track member in transverse
section; Fig. 2, a fragmentary sectional per-
spective view of the parts in a disconnected
condition; Fig. 3, a similar view of the parts
in a connected condition; Fig. 4, a detail hori-
30 zontal section at line *x x*, Fig. 1, illustrating
a modification of the present invention.

Similar numerals of reference indicate like
parts in the several views.

Referring to the drawings, 1 represents the
35 supporting-bracket, which in my preferred
form, as shown in the drawings, is formed
from a piece of plate or bar metal bent upon
itself, with the respective ends of such plate
or bar bent at right angles to the body por-
40 tion of the bracket to constitute attaching-
ears 2, by means of which the bracket can be
secured in place upon a wall or other surface.
With such construction the end formed by
bending such plate or bar upon itself is adapt-
45 ed for engagement with the track or other
rail of the present construction, as will here-
inafter more fully appear.

3 represents a track or other rail of a usual
cross-section, preferably the crucial shape
50 shown in the drawings, and which rail is pro-
vided with orifices along its length and about

midway its height for engagement with the
projecting ends of the brackets 1. In the
present invention such attachment between
the rail and the bracket is attained in a cheap 55
and efficient manner by a construction of
parts as follows:

4 is a socket notch or recess formed at one
side of the rail-engaging end of the bracket 1
and having a width equal to the thickness of 60
the web of the rail.

5 is one of the before-mentioned orifices
through the web of rail 3 of a shape corre-
sponding with that of the rail-engaging end
of the bracket 1 of length sufficient to admit 65
of the insertion of such bracket end through
such orifice, with the socket-notch 4 in aline-
ment with the web of the rail. With such
construction an independent longitudinal ad-
justment of one of said parts with relation to 70
the other, so that the socket-notch 4 will en-
gage with the web of the rail, as indicated in
Fig. 3, after which disengagement of the parts
in a reverse direction will be prevented by
means of a key or filling-piece 6, secured in 75
the rail-orifice 5 at the end of the same oppo-
site to that at which the socket-notch 4 has
engagement. Such key or filling-piece may
be formed as a separate piece 6', as shown in
Fig. 4, and upset or riveted in place. It is 80
preferable, however, to form such filling-piece
integral with the web of the rail and in the
form of tongue or lip 6, formed in manner
well understood in the present art in the op-
eration of punching the orifice 5. With such 85
last-mentioned construction the tongue or lip
6 will set to one side of the rail-web, as shown
in Fig. 2, until after the parts are assembled
together in proper relative position, and then
hammered or set down to a level with the sur- 90
face of the rail-web, as illustrated in Fig. 3.

The present improved construction affords
a very cheap and at the same time strong and
durable attachment between the rail and
bracket and admits of the lower portion of 95
said rail being left unobstructed to permit of
the use of a secondary or keeper-track roller
where such use is desired in any particular
use of the present invention.

The crucial form of track shown in the 100
drawings is preferred, where a very strong and
rigid attachment is desired, in that one of the

horizontal webs of the track-rail of such form 5
can rest directly on top of the bracket and be
supported thereon, so as to remove a greater
portion of the downward stress upon the pres-
ent means of attachment in actual use.

While my present improvement is specially
adapted for use as a track for barn-door han-
gers, it is applicable to a number of other uses
in the allied arts, and therefore the scope of
10 the present invention is intended to cover
such various uses of the present improved
construction.

Having thus fully described my said inven-
tion, what I claim as new, and desire to secure
15 by Letters Patent, is—

1. A rail and bracket connection, comprising
a bracket end formed with a socket-recess
at one side adapted for engagement with
the web of the rail, a rail formed with an ori-
fice corresponding with the end of the bracket
20 and adapted to receive said bracket end, en-
gagement of the rail and the socket-recess
being had by an independent longitudinal
adjustment of one of said parts, and means
25 for locking the parts at such longitudinal
adjustment, substantially as set forth.

2. A rail and bracket connection, comprising
a bracket end formed with a socket-recess
at one side adapted for engagement with
30 the web of the rail, a rail formed with an ori-
fice corresponding with the end of the bracket
and adapted to receive said bracket end, en-
gagement of the rail and the socket-recess
being had by an independent longitudinal
35 adjustment of one of said parts, and means
for locking the parts at such longitudinal
adjustment, the same comprising a filling-
piece inserted in the rail-orifice at the end of

the same opposite to that at which the socket-
recess has engagement, substantially as set 40
forth.

3. A rail and bracket connection, comprising
a bracket end formed with a socket-re-
cess at one side adapted for engagement with
the web of the rail, a rail formed with an ori-
fice corresponding with the end of the bracket
45 and adapted to receive said bracket end, en-
gagement of the rail and the socket-recess
being had by an independent longitudinal
adjustment of one of said parts, and means 50
for locking the parts at such longitudinal ad-
justment, the same comprising a filling-piece
or tongue formed integral with the rail-web
and adapted for engagement with the side of
the bracket opposite to the side in which the 55
socket-recess is formed, substantially as set
forth.

4. A rail and bracket connection, comprising
a bracket end formed with a socket-recess
at one side adapted for engagement with 60
the web of the rail, a rail having a crucial
form and provided with an orifice imme-
diately beneath the horizontal webs of such
rail and adapted to receive the engaging end
of the bracket, engagement of the rail and 65
the socket-recess being had by an independent
longitudinal adjustment of one of said parts,
and means for locking the parts at such lon-
gitudinal adjustment, substantially as set
forth. 70

Signed at Sterling, Illinois, this 11th day
of January, 1902.

JOHN H. LAWRENCE.
